UNITED STATES PATENT OFFICE.

HARRY H. IDE, OF LA GRANGE, ILLINOIS, ASSIGNOR TO KELLOGG SWITCH BOARD AND SUPPLY COMPANY, OF CHICAGO, ILLINOIS, A CORPORATION OF ILLINOIS.

CALLING DEVICE.

Application filed December 18, 1920. Serial No. 431,561.

My invention relates to calling devices such as are used in automatic and semi-automatic telephone systems for controlling the automatic switches which are located at the central office and are used for establishing connections between calling and called subscribers, and has to do more particularly with the new and improved motor spring adjusting means for a calling device whereby the proper tension may be given to the said motor spring.

Calling devices of the art are provided with motor springs which are placed under a certain tension. When the setting member of the calling device has been advanced, the said setting member is restored to normal by means of the said motor spring, and a train of gearing associated with the calling device is set in motion, by the return of the setting member to normal, to operate the impulse mechanism, thereby transmitting a predetermined number of impulses to the automatic switches. Various methods have been employed for adjusting the motor spring of the calling device to its proper tension, all of which are somewhat complicated and necessitate special tools for operating the adjusting means to place the motor spring under proper tension.

30 A feature of my invention is the provision of a new and improved adjustable spring tension means, which is simple in construction and in which no special tools are needed for adjusting the tension of the motor spring. The motor spring tensioning device of my invention embodies desirable features and advantages in a simple, efficient and economical manner. These features will be more fully described in the ensuing specification.

For a more complete understanding of my invention, reference may be had to the accompanying drawing, in which I illustrate the motor spring tensioning device of my invention, in the several views, operatively associated with the calling device, and in which like reference characters in the several views denote like parts, and in which

Fig. 1 is a face view of the calling device;
50 Fig. 2 is a rear view of Fig. 1, showing my invention;

Fig. 3 is an interior view of the calling device, showing the mechanism of the same;

55 Fig. 4 is a side view of the calling device with parts broken away to more clearly il-

lustrate the application of my invention to the calling device;

Fig. 5 is a sectional view of the motor spring and its supporting parts;

Fig. 6 is a disassembled perspective view of the adjustable motor device and its associated parts; and

Fig. 7 is a view similar to Fig. 5, but with the motor spring tensioning device in its depressed position to permit adjustment of the motor spring.

As my invention relates particularly to a motor spring tensioning device, a detailed description of the mechanism of the calling device as illustrated in the accompanying drawing will not be given, but only such description as is necessary for a full and complete understanding of the adjustable motor device. For a more complete understanding of the calling device, reference may be had to Patent No. 1,501,281, issued July 15, 1924.

Referring now more in detail to my invention as illustrated, the calling device associated with the adjustable motor device comprises a main mounting plate A which supports the calling device mechanism, a finger-hold actuating member B and a bridge plate C for supporting the parts of the calling device. The main shaft 4 extends through a suitable bearing sleeve 5 secured to the main mounting plate A and a bearing sleeve 6 which is secured to the bridge plate C in any suitable manner, said shaft 4 rotating the said bearings 5 and 6. A sleeve 7 is provided which is of a size to receive the shaft 4, said sleeve 7, when in place, resting against the bearing 5. The finger-hold actuating member B is secured to the forward end of the shaft 4 by means of a screw 8, which screw has screw-threaded engagement with a suitable tapped orifice in the forward end of the main shaft 4.

The forward end of the shaft 4 is cut away to form a squared portion, and the finger-hold actuating member B is provided with an opening to conform with the squared end of the shaft 4, and this squared portion of the shaft 4 and opening in the finger-hold actuating member B thus secures the said member B against rotation on the shaft 4 when it is advanced from its normal position. The finger-hold actuating member B is provided with a plurality of openings or finger-holds 80 for the usual advancing purposes, and a stationary finger-stop 9, secured

to the mounting plate A by means of the screws 10, is provided so that when the finger-hold actuating member B is advanced in a clockwise direction, the advancing finger 5 of the operator engages the stationary stop 9 and arrests further movement of the actuating member B.

The motor spring tensioning device MS comprises a spiral motor spring 11 which is 10 coiled about bearing 5 and the sleeve 7, and the end 12 of the motor spring 11 is inserted into opening 13 in the main mounting plate A. A disc 73 is provided having a plurality of notches 14 cut in its periphery 15. It is 15 also provided with a centrally located orifice 16 of a size to permit the said disc 73 to be slipped over the sleeve 7 and permit its rotation about the sleeve 7 for purposes as will presently be described. The other end 17 of 20 the motor spring 11 is inserted into an orifice 18 in the disc 73. Thus, one end 12 of the motor spring 11 rests in the orifice 18 in the mounting plate A, and the other end 17 rests in the orifice 18 of the said disc 73. A detent 25 19 is provided which has a squared orifice of a size to receive the squared portion 21 of the shaft 4 and is held in place by means of a screw 22, which screw has screw-threaded engagement with a suitable tapped orifice in 30 the end of the shaft 4.

The motor spring 11 rests between the face of the main mounting plate A and the disc 73, and its longitudinal tension is such that it forces the said disc 73 against the bottom 35 face 23 of the detent 19. The detent 19 is provided with an angular extension 24 which is of a size to permit it to rest in one of a plurality of notches 14 in the periphery 15 of the disc 73. To adjust the motor spring 40 11 to its proper torsional tension, the disc 73 is grasped by the fingers of the person adjusting the said spring 11 and forced downward against the longitudinal tension of the motor spring 11 until the notch 14 in the periphery 15 of the disc 73, in which the angular extension 24 of the detent 19 rested, clears the same, as clearly illustrated in Fig. 7. Now, when the disc 73 is in this position, and as it is loosely mounted upon the sleeve 7, the 45 said disc 73 may be rotated in a counter-clockwise direction, by referring to Fig. 2, and as the end 17 of the motor spring 11 is inserted in the orifice 18 in the disc 73, this counter-clockwise rotation of the disc 73 50 winds up the motor spring 11 to give it more torsional tension. Now, when a notch 14 in the disc 73 registers with the angular extension 24 of the detent 19, the downward pressure upon the disc 73 may be released and the 55 disc 73 is now moved upward due to the longitudinal tension of the spring 11, allowing the angular extension 24 of the detent 19 to enter a notch 14 in the disc 73. The face 25 of the disc 73 rests against the bottom face 23 of the detent 19, which face 23 acts as a

stop for the said disc 73 when forced upward by the longitudinal tension of the motor spring 11. To lessen the tension of the motor spring 11 the disc 73 is forced downward, as before described, against the longitudinal tension of the spring 11, depressing the same until the angular extension 24 of the detent 19 clears the notches 14 in the said disc 73. This permits the disc 73 to be rotated in a clockwise direction, by referring to 75 Fig. 2, and when a notch 14 of the disc 73 registers with the angular extension 24 of the detent 19 the downward pressure is released from the said disc 73 and the longitudinal tension of the motor spring 11 forces 80 the disc upward until the extension 24 again enters a particular notch 14 in the disc 73, thus holding the motor spring to its adjusted torsional tension.

The detent 19, when the calling device is at 85 normal, engages an insulating buffer located on one of a pair of shunt springs as illustrated in Figure 2 of the accompanying drawing. The two middle contact springs are normally held apart by the engagement 90 of the detent 19 and the buffer. When the shaft 4 is rotated the detent 19 rotates with it and disengages the buffer and allows the contact springs to engage each other to form a shunt circuit to short circuit the subscriber's apparatus while the impulses are being sent. For a fuller description of the apparatus reference may be had to Patent Number 1,501,281 issued to me July 15, 1924.

Mounted upon the main shaft 4 is a gear 100 wheel 30, which gear wheel 30 in turn meshes with a pinion 31, which pinion 31 is integrally formed with the shaft 32, the said shaft 32 also carrying the governor mechanism G of the calling device. The shaft 105 32 also carries a gear wheel 33, which meshes with a pinion 34 integrally formed upon the shaft 35, which shaft 35 also carries the cam member 36 for opening and closing the impulse springs I of the calling device. 110 This train of gearing thus outlined is connected to the main shaft 4 to the governor mechanism G and impulse mechanism I, the said governor G permitting the return movement of the finger-hold 115 actuating member B at a predetermined speed through the agency of the motor spring 11. Now, when the finger-hold actuating member B is rotated in a clockwise direction to set the calling device to 120 permit a certain number of impulses, the gear wheel 30 and the floating ratchet 46, which are loosely mounted upon the main shaft 4, remain stationary while the shaft 4 and the dog 181 are operated in a clockwise direction so that the arms 37, 38 and 39 ride over the wings 40 of the floating ratchet 46 until the arms 37 and 38 rest in the desired wing 40 of the floating ratchet 46. Due to 125 the fact that the detent 19 is secured to the 130

shaft 4 by means of its squared opening 20 and screw 22, the said detent 19 is also carried with the shaft 4, and as the angular extension 24 engages a notch 14 in the disc 73, the disc 73 is also carried with the said main shaft 4, and as the end 17 of the motor spring 11 rests in the orifice 18 of the said disc 73, it brings about the winding up of the motor spring 11 upon the forward rotation of the finger-hold actuating member B. Upon the return movement of the finger-hold actuating member B, the shaft 4 and dog 131, all of which are secured to the shaft 4, also return therewith, as the arms 37 and 38 of the dog 131 now engage the desired wing 40 of the ratchet 46. Downwardly extending arms 41 and 42 of the ratchet 46 extend into the orifices 43 and 44 in the gear wheel 30, and the gear wheel 30 is thus rotated therewith, and through the medium of the train of gearing the motion is transmitted to the governor shaft 33 and the cam actuating shaft 35 to transmit a group of impulses.

While I have illustrated and described my invention operating in connection with a certain type of automatic calling device, I do not wish to be limited to the same, as my invention may be adapted to cooperate in conjunction with other devices, and changes and modifications may readily suggest themselves to one skilled in the art. Therefore, I do not wish to be limited to the exact structure as shown, but aim to cover all such changes and modifications as come within the spirit and scope of the appended claims.

Having described my invention what I claim as new and desire to secure by Letters Patent is:

1. An impulse transmitter for automatic telephone systems, comprising a rotary shaft, a finger hold device to rotate said shaft, a coil spring to rotate said shaft when released and transmit the impulses, said spring having an unadjustable connection with a member of said device, a second member of said device connected to said spring and rotatable by hand with respect to said shaft, to adjust the torsion of said spring, apparatus including a radially extending detent fixed to the shaft, and means on said second member to be engaged thereby to hold said spring under any of its adjustable torsions with respect to the shaft, and contact springs controlled by said detent.

2. In an impulse device for automatic telephone systems, the combination with a rotary shaft to transmit the impulses, of a spring to drive said shaft, two members engaging one another one fast with the shaft and adapted to control a pair of contact springs the other fast with the spring, said member fast with said spring being adapted

to be disengaged by hand from said member fast with the shaft and rotated to adjust the torsion of said spring and to again reengage said member fast with the shaft to maintain a changed torsion of the spring on the shaft.

3. The combination with a rotary shaft and a support with a bearing therefor, of a coil spring about said shaft having one end in fixed relation to said support and the other end adjustably fixed to said shaft by means comprising a disk rotatable by hand with respect to said shaft, said disk provided with peripheral means for engagement by a detent fixed with respect to said shaft, said means and said detent serving to adjust and maintain any adjustment made of the torsion of said spring on the shaft, and contact springs controlled by said detent.

4. In an impulse sending device the combination of a rotatable shaft, a coil spring for rotating said shaft back to a normal point, a detent fixed to said shaft having a depending portion, a pair of contact springs controlled by said detent, a member rotatable with relation to said shaft and connected to one end of said spring, said member adapted to be rotarily adjusted by hand to increase or decrease the torsional force of said spring, and means comprised in said member for operative engagement by the depending portion of said detent to maintain said spring under any of its adjustable tensions.

5. In an impulse sending device the combination of a rotary shaft and a support therefor, a spring to rotate said shaft having one end fast to the support, and the other end adjustably connected to the shaft, the connecting means comprising a part fixed with the shaft having a depending portion and a part fixed with the spring, having a plurality of peripheral notches adapted to be engaged by said depending portion, said parts extending radially from the shaft to engage one another and adapted to be pressed apart by hand to disengage to allow the torsion of the spring to the shaft to be adjusted, and the parts re-engaged to allow said depending portion to enter one of said peripheral notches to maintain the said spring in its adjusted torsion, and a pair of contact springs controlled by the said part fixed to the shaft.

6. An impulse transmitter for automatic telephone systems comprising a rotary shaft, means for rotating said shaft, a motor spring for said shaft for rotating the same when means are released to restore said shaft, a fixed connection for one end of said spring with a member of said impulse transmitter, a disk slidably and rotatably supported on said shaft and connected to the other end of said spring and rotatable by hand to adjust the torsion of said motor

spring, a detent fixed to said shaft controlling a pair of contact springs and engaging means on said disk including peripheral notches adapted to be engaged by a depending portion of said detent to hold said motor spring in an adjusted torsion.

7. An impulse transmitter for automatic telephone systems comprising a rotary shaft, a motor spring to rotate said shaft having one end in fixed connection with a member of said impulse transmitter, a disk slidably and rotatably supported on said shaft and connected to the other end of said motor spring, a detent fixed to said shaft, a pair of contact springs controlled by said detent engaging means on said disk comprising peripheral notches adapted to be engaged by a depending portion of said detent and held in this engaging position by means of the longitudinal tension of said motor spring, said disk being adapted to be moved longitudinally in relation to said shaft by hand to permit the torsion of the spring to be adjusted by rotating the disk and to permit said disk to be moved to again be engaged by said detent to maintain the adjusted torsion of said motor spring.

8. In an impulse transmitter of the class described comprising a rotary shaft, a motor

spring for rotating said shaft having one end fixed to a member of said impulse transmitter, and the other end adjustably secured to the said shaft, a disk slidably and rotatably supported on said shaft and connected to said motor spring and a detent fixed to said shaft forming the connecting means between said spring and shaft, said disk being held normally in engagement with said detent under longitudinal tension of said spring to hold said spring in an adjusted torsion, said disk being adapted to be disengaged from said detent by downward pressure by hand against the longitudinal pressure of said spring and rotated independently of said shaft to permit the torsion of said spring to be increased or decreased, said longitudinal tension of said spring again forcing said disk into engagement with said detent when the desired adjustment of said spring is obtained to permit said detent to hold said spring in its adjusted torsion and a pair of contact springs controlled by said detent.

Signed by me at Chicago, in the county of Cook and State of Illinois, this 16th day of December, 1920.

HARRY H. IDE.
